ATTORNEY.

UNITED STATES PATENT OFFICE.

EDWARD D. PUTT, OF AKRON, OHIO, ASSIGNOR TO THE FIRESTONE TIRE AND RUBBER COMPANY, OF AKRON, OHIO, A CORPORATION OF OHIO.

STRIP-COVERING MACHINE.

Application filed March 3, 1927. Serial No. 172,882.

This invention relates to machines for covering strip material and particularly to machines for applying and binding a band of fabric about a core of strip material.

5 An object of the invention is to provide means for assembling a core of strip material and a band of fabric, means for folding or wrapping the fabric about the core, and means for stitching or binding the 10 fabric to the core.

The foregoing and other objects are obtained by the device illustrated in the accompanying drawings and described below. It is to be understood that the device is not 15 limited to the specific form thereof disclosed herein.

Of the accompanying drawings:

Figure 1 is a front elevation of a machine embodying the principles of the invention; 20

Figure 2 is a plan thereof; and

Figure 3 is an elevational detail on an enlarged scale of a portion of the device.

Referring more particularly to the drawings, 10 represents the table or bed of the

25 machine, having attached thereto a bracket 11 upon which is mounted a core or strip guiding tube 12 and a fabric guide plate 13. Guide bar 14 is adjustably clamped to

plate 13 to accommodate different widths of 30 fabric band 15 guided thereover, said band being taken from a supply reel (not shown)

and passed under bars 16 and 17. The core 18 of strip material to be covered is drawn through guide tube 12 from a supply reel

35 (not shown) by a driven feed roller 19, splined on shaft 20 and having a series of

different-sized grooves for engaging various sizes of cores 18. Roller 19 is shiftable along shaft 20 to align any desired groove

40 with guide tube 12 and a spring pressed pressure roller 19^a for retaining the core in

the tube. When roller 19 is properly adjusted, it is fixed in position and core 18 is passed between the groove and pressure roller 19^a.

45 Band 15 and core 18 are then passed together through a fixed, fabric folding tube 21 having a cam surface 22 for folding or wrapping band 15 about core 18.

While a single strip of fabric may be employed, band 15 is preferably composed of

50 two layers of bias-cut fabric of the same width, but with oppositely projecting edges, so that when the band is folded around the core, the edges of each layer of fabric will

55 abut, respectively, and the seam in the outer

layer overlap the seam in the inner layer. Each layer of fabric is rubberized or coated with cement to cause the layers to adhere to each other and to the core. A sheet metal guard 23 is attached to the forward end of 60 tube 21 to prevent the fabric from touching and adhering to the core before being entirely wrapped around the latter.

In order to stitch or compress band 15 more securely about the core, the wrapped

65 core is passed through the central aperture 24 of rotatable disc 25 journaled in bracket 26 attached to table 10. The free end of

stitcher arm 27 pivoted to disc 25, is yieldingly pressed against the wrapped core by

70 tension spring 28, so that the wrapping is tightly stitched down when disc 25 is rapidly rotated by belt 29 trained over disc 24 and pulley 30 fixed to motor shaft 31,

75 proper balance of disc 25 being maintained by a counterweight 32 attached thereto.

From disc 25 the covered strip passes through an aperture in guide bracket 33 to a driven feed roller 34, being forced against

80 said feed roller by a spring-pressed roller 35. Feed roller 34 is keyed to shaft 36, driven by a chain 37 from shaft 20, which

85 is in turn driven from motor shaft 31 through suitable reduction gears 38 and 39 and chain 40, whereby the feed rollers may be slowly rotated.

As the covered strip passes from the machine it may be wound on a reel (not shown) with a drive and level-wind mechanism connected to motor-shaft 31 in any suitable 90 manner as will be understood.

Modifications of the invention may be resorted to without departing from the spirit thereof or the scope of the appended claims.

What is claimed is:

1. A strip covering machine comprising a guide for a core of strip material, a guide for a band of fabric to be fed into said machine, a feed roller for drawing said core into the machine, a folding tube through

100 which said core and band may be passed for wrapping the band of fabric about the core, a disc journaled about the end of said tube and adapted to be rapidly rotated, a spring-

105 pressed pivoted stitcher arm carried by said disc with the free end of said arm adjacent the center of said disc, said disc having a central aperture through which the covered strip may be passed, whereby pressure of the

110 pivoted arm rapidly rotated by the disc will

stitch the fabric band tightly about the core, and a feed roller for drawing the finished product from the machine.

2. A strip covering machine comprising in combination, means for slowly feeding and guiding into said machine a core of strip material and a band of fabric to be wrapped thereabout, means for folding the band of fabric about the core, means for preventing the unwrapped portion of the band from prematurely adhering to the core, a centrally apertured disc journaled adjacent

said folding means and adapted to be rapidly rotated, a spring-pressed pivoted stitcher arm carried by said disc with the free end of said arm adjacent the center of said disc, whereby pressure of the pivoted arm rapidly rotated by the disc will stitch the fabric band tightly about the core as the wrapped core is slowly passed axially through the aperture in the disc, and means for drawing the finished product from the machine.

EDWARD D. PUTT.
